UNITED STATES PATENT OFFICE

2,047,098

INGOT MOLD

Emil Gathmann, Baltimore, Md.

Application August 2, 1934, Serial No. 738,128

7 Claims. (Cl. 22—139)

This invention relates to ingot molds and more particularly to ingot molds having vertically extending chamber-defining walls necked-in at their bottoms, of the kind shown for example in my prior United States Patents 1,188,751 of June 27, 1916; 1,660,037 of Feb. 21, 1928; 1,573,486 of Feb. 16, 1926; 1,570,473 of Jan. 19, 1926 and others well known in the art.

In my Patent 1,188,751, referred to above, I have disclosed and claimed a metallic ingot mold the lower portion of which has concave walls which merge with convex walls the latter in turn being tangent to and merging with the walls of an opening extending vertically through the mold bottom. This general type of bottom contour has been employed in many thousands of tons of molds used in the commercial production of ingots, these molds having been found to produce a consistently high grade ingot both as regards the crystalline structure of the lower end of the ingot and the ease with which the ingot can be handled during the rolling process, particularly during the initial mill passes.

A practical difficulty with molds of the kind disclosed in the patents referred to above is that because of the lower or convex walls being tangent to or merging with the walls of the mold bottom opening and having rather small radii, (i. e. small as compared to the mean width of the mold chamber proper), there is provided a "hump" or protuberance extending around and just above the mold bottom opening which is particularly vulnerable to the cutting action of the hot liquid steel as it splashes laterally from the closure within the bottom opening. This has resulted in premature erosion of the convex portion and consequently in shortened mold life, since cutting away of this part of the mold wall results in poor surface at the bottom of the ingot. This has been objected to by steel makers for a number of years but has been put up with as part of the necessary additional cost of producing the kind of ingot desired.

An object of the present invention is to eliminate as far as possible this localized and premature erosion or cutting away of the portion of the mold wall surrounding and just above the mold bottom opening, yet providing a bottom contour which will produce ingots having the improved qualities of ingots produced in molds of the kind disclosed in the prior patents referred to.

Generally stated, my invention consists in the provision of a mold having a chamber-defining

wall which is necked-in at its bottom, terminating in a vertically extending mold bottom opening, the necked-in portion of the wall comprising a concave part which merges with the mold wall proper and a preferably convex part connected to the concave part and intersecting but not being tangent to the wall of the mold bottom opening, the arrangement being such that the objectionable "hump" or protuberance previously referred to is practically eliminated. In its more specific nature the invention resides in the provision of a bottom contour embodying a specifically novel and improved arrangement of curved wall portions having radii bearing specific relative proportions to each other and to other dimensions of the mold.

The invention will be more clearly understood from a reading of the following description of a typical embodiment, the appended claims, and the accompanying drawing, in which:

Figure 1 is a vertical sectional view of a mold embodying the invention, the section being taken on the line 1—1 of Figure 3;

Figure 2 is a vertical sectional view taken on the line 2—2 of Figure 3;

Figure 3 is a horizontal sectional view taken on the line 3—3 of Figure 1; and

Figure 4 is a fragmentary view in vertical cross section taken on the line 4—4 of Figure 3 and drawn on an enlarged scale.

For the purpose of illustration the drawing shows a big-end-up mold M of the Gathmann type generally rectangular in horizontal cross section and having side walls 1 which are corrugated in horizontal cross section, although it will be understood that the invention may be embodied in molds having other horizontal sectional contours. The walls 1 are connected by corner walls 2, the walls 1 and 2 being continuous and therefore together constituting a mold wall proper extending around and defining the mold chamber. The bottom of the mold is formed with a centrally disposed bottom opening 3 the width a of which preferably is relatively small as compared to the approximate mean width b of the mold chamber. For example, in the mold shown the width a may be about one-third the width b. A closure plug P of a well known kind is shown positioned in the opening 3.

The wall 1—2 is necked-in at its bottom, the necked-in portion X terminating at the mold bottom opening, and in accordance with one feature of the invention, the necked-in portion intersects the upper marginal edge of the bottom opening as at 3'; i. e., the necked-in portion, if

continued, would extend to within the opening 3 as indicated by the dotted lines 32.

The necked-in portion X comprises a concave part 4 which merges with the mold wall proper 1-2, a substantially straight, (i. e straight in vertical cross section), inwardly tapered part 5 which is tangent to the concave part 4, and a convex part 6 which is tangent to and merges with the substantially straight part 5 and which intersects the bottom opening 3 at its upper marginal edge 3'. It is important in order to avoid the formation of a hump or protuberance around the top of the opening 3 that the convex part 6 should not be tangent to the wall of the opening—in other words, the convex part should intersect the upper marginal edge of the opening, and the continuation 32 of the convex part should extend to within the opening 3. To provide this desired arrangement I employ a convex part 6 having a radius R at least as long as the radius R' of the concave part 4 and preferably a little larger, and I locate the centers C and C' of the curved parts 6 and 4 in general accordance with the arrangement shown in Figure 4.

It will be understood that the specific lengths of the radii and positioning of the centers may vary depending somewhat upon the specific size and type of mold. By way of example, however, in the mold shown, which has a chamber approximately sixty-four inches in height and about twenty inches in mean width b, the following dimensions are preferred: The width a of the top of the bottom opening 3 is about six inches and the depth d of the opening may also be about six inches. The radius R' of the concave part 4 is about three and one-half inches and is located a distance e (about six inches) above the top of the bottom opening 3. The length of the radius R is about five inches and the center C is located a distance f (about three and one-half inches) below the top of the bottom opening 3 and a distance g (about six inches) from the vertical center line of the bottom opening. Preferably the radius R is about one-fourth as long as the mean width b of the mold chamber and the radius R' is about one-sixth as long as b. The bottom walls of molds having a bottom contour such as described herein have been found to be much less susceptible to the cutting action of the molten steel than molds having contours such as those disclosed in the prior patents referred to.

Obviously the numerical dimensions stated above will vary in molds of different sizes and it will be understood that the invention resides in the provision of the kind of mold bottom contour described herein and particularly pointed out in the appended claims.

I claim:

1. An ingot mold having a vertically extending chamber defined by a wall which is necked-in at the bottom terminating in a mold bottom opening of relatively small width as compared to the width of the mold chamber, the necked-in portion of the wall comprising a concave part which merges with the mold wall proper and a convex part connected to the concave part and which, in section longitudinally of the mold, intersects but is not tangent to the wall of the mold bottom opening.
2. An ingot mold having a vertically extending chamber defined by a wall which is necked-in at the bottom terminating in a mold bottom opening of relatively small width as compared to the width of the mold chamber, the necked-in portion of the wall comprising a concave part which

merges with the mold wall proper and a convex part connected to the concave part and intersecting the upper edge of the wall of the mold bottom opening, the continuation of the arc of said convex part extending inwardly beyond the walls of and into said mold bottom opening. 5

3. An ingot mold having a vertically extending chamber defined by a wall which is necked-in at the bottom terminating in a mold bottom opening of relatively small width as compared to the width of the mold chamber, the necked-in portion of the wall comprising a concave part which merges with the mold wall proper, a substantially straight inwardly tapered part tangent to said concave part, and a convex part 15 connected to the substantially straight part and intersecting the upper edge of the wall of the mold bottom opening, the continuation of the arc of said convex part extending inwardly beyond the walls of and into said mold bottom 20 opening.

4. An ingot mold having a vertically extending chamber defined by a wall which is necked-in at the bottom terminating in a mold bottom opening of relatively small width as compared to the width of the mold chamber, the necked-in portion of the walls comprising a concave part which merges with the mold wall proper, a substantially straight inwardly tapered part tangent to said concave part, and a convex part 30 connected to the substantially straight part and intersecting the upper edge of the wall of the mold bottom opening, the continuation of the arc of said convex part extending inwardly beyond the walls of and into said mold bottom 35 opening, the radius of said convex part being at least as long as the radius of the concave part.

5. An ingot mold having a vertically extending chamber defined by a wall which is necked-in at the bottom terminating in a mold bottom opening of relatively small width as compared to the width of the mold chamber, the necked-in portion of the wall comprising a concave part which merges with the mold wall proper, a substantially straight inwardly tapered part tangent to said concave part, and a convex part 40 connected to the substantially straight part and intersecting the upper edge of the wall of the mold bottom opening, the continuation of the arc of said convex part extending inwardly beyond the walls of and into said mold bottom opening, the radius of the convex part being at least as long as the radius of the concave part. 45

6. An ingot mold having a vertically extending chamber defined by a wall which is necked-in at the bottom terminating in a mold bottom opening of relatively small width as compared to the width of the mold chamber, the necked-in portion of the wall comprising a concave part 55 which merges with the mold wall proper, a substantially straight inwardly tapered part tangent to said concave part, and a convex part connected to the substantially straight part and intersecting the upper edge of the wall of the mold bottom opening, the continuation of the arc of said convex part extending inwardly beyond the walls of and into said mold bottom opening, the radius of the concave part being about one-sixth as long as the mean width of the chamber proper and the radius of the convex part being about one-fourth as long as the mean width of the chamber proper. 60

7. An ingot mold having a vertically extending chamber defined by a wall which is necked- 70

in at the bottom terminating in a mold bottom opening of relatively small width as compared to the width of the mold chamber, the necked-in portion of the wall comprising a concave part which merges with the mold wall proper and a lower part connected to the concave part and

intersecting but not being tangent to the upper edge of the wall of the mold bottom opening, the continuation of the line of said lower part extending into said mold bottom opening.

5 EMIL GATHMANN.
